UNITED STATES PATENT OFFICE.

WILLIAM CARTER, OF LONDON, ENGLAND.

UMBRELLA AND PARASOL.

SPECIFICATION forming part of Letters Patent No. 244,545, dated July 19, 1881.

Application filed May 7, 1881. (No model.) Patented in England April 4, 1879, in France October 4, 1879, and in Belgium October 7, 1879,

To all whom it may concern:

Be it known that I, WILLIAM CARTER, of London, England, have invented new and useful Improvements in Umbrellas and Parasols, (for which I have obtained a patent in Great Britain, No. 1,346, bearing date April 4, 1879, a patent in France, No. 133,011, bearing date October 4, 1879, and a patent in Belgium, No. 49,487, bearing date October 7, 1879,) of which 5 the following is a specification, reference being 10 had to the accompanying drawings.

My invention relates to improvements in umbrellas and parasols, and is designed to provide better means than any heretofore in use 15 for securing the upper end or tip of the ribs to the fixed ring or "top notch," and for securing the lower end or tip of the stretchers to the sliding piece or runner.

It also relates to forming the lower end or 20 tip of such ribs as are made with a groove running lengthwise, as in the so-called well-known "paragon-frames," with a flattened portion, whereby such ribs will lie closer to the stick when the umbrella or parasol is closed than 25 heretofore.

The said invention is illustrated in the accompanying drawings, in which—

Figure 1 represents a portion of an umbrella-stick and the top notch and runner, and shows 30 my improved ribs and stretchers applied thereto. Fig. 2 is an interior view of the upper end of a rib constructed according to my invention; and Fig. 3 is a longitudinal section of the top notch, showing my improved ribs 35 attached thereto. Fig. 4 is a side view of portions of a stretcher constructed according to my invention, and Fig. 5 is an interior view of the same. Fig. 6 shows the method of securing the stretchers to the runner. Fig. 7 is a side 40 view, and Fig. 8 is an interior view, of the lower or outer end of an umbrella-rib constructed according to my invention. Figs. 2 to 8 are drawn to an enlarged scale.

Like letters indicate the same parts throughout the drawings.

a represents the stick of the umbrella, *b* the top notch, and *c* the runner. *d d* are the ribs, and *e e* are the stretchers, for the same.

In carrying my invention into practice, instead of forming the said ribs and stretchers

with thin, flat, and elongated ends, to be attached to the top notch and runner, I make the said ends or eyes of a round or curved form, as shown at *d' e'*, and of a comparatively great width or thickness—that is to say, considerably thicker than these parts have heretofore been made. This form is obtained by turning over a portion of the metal of which the rib or stretcher is constructed, an aperture being left for the passage of the ordinary wire for securing the tip to the top notch or runner. These eyes or ends *d'* or *e'* are preferably formed of the same or nearly the same width or thickness as the ribs or stretchers, and fit into apertures *b' c'*, of corresponding width, provided 60 in the top notch, *b*, and the runner *c*. The said top notch and runner are somewhat similar to those heretofore constructed, but are smaller in diameter, the apertures therein are wider, and the projections are deeper than those in 70 the top notches and runners heretofore employed. The tips or ends *d'* and *e'* are secured to the said top notch and runner by passing a wire, *f*, through the aforesaid tips or ends in the ordinary manner.

I prefer to form the runner with a curved flange or ring, *c'*, upon whose upper edge the ends *e'* of the stretchers rest when secured in position, as shown in Fig. 6.

It will be seen that by forming the tips or 80 ends *d'* and *e'* as above described, and by constructing the ribs or projections *b'* and *c'* on the top notch and runner deeper than heretofore, I insure a larger bearing-surface for the ribs and stretchers than is possible with the 85 flat thin heads heretofore employed, and the ribs and stretchers therefore open and close in a direct manner without any liability to become crossed, twisted, or obstructed. Moreover, by forming the top notch and runner of 90 small diameter, as above described, I obtain the further important advantage of causing the ribs and stretchers to lie closer to the stick when the umbrella is closed than heretofore.

Each rib *d* and each stretcher *e* is formed of 95 a piece of metal bent or doubled longitudinally along its length to form two longitudinal flanges; and in order to further increase the strength of the ends *d' e'* of the said ribs and stretchers, I turn over a portion of the flanges 100

of the said ribs and stretchers, as shown at d^* 20
 e^* , thereby providing a greater thickness of metal at those parts.

Instead of forming the lower end or tip of the ribs with the usual projecting knobs, I form the same with a knob, d^2 , which is cut away or flattened upon the inner side, as shown at d^3 25 in Figs. 7 and 8, so that the rib will lie closer to the stick when the umbrella is closed than heretofore.

Heretofore umbrella ribs and stretchers have been formed with broadened flat-eyed ends fitting broad notches in the crown-piece and runner, and confined in place by wires, but such is not broadly claimed by me.

What I claim is—

1. The longitudinally-flanged umbrella-rib herein described, having an eyed end formed of the same width as the rib, and the ends of

the side flanges of the rib turned or folded inward toward each other beneath the broadened eyed end, substantially as and for the purpose described.

2. A longitudinally-flanged stretcher for the ribs of umbrellas, having an eyed end formed 25 of the same width as the stretcher, and the end portions of the flange of the stretcher turned or folded inward toward each other beneath the eyed end, substantially as described.

3. An umbrella or parasol rib having its 30 outer free end provided with an enlarged laterally-projecting knob, d^2 , having its inner side formed with a straight flat face, d^3 , substantially as and for the purpose described.

WILLIAM CARTER.
